ELECTROCHEMICAL SALVAGING METHOD

Anthony J. Fusco, Belleville, N. J., and Jerome L. Bleiweis, New York, N. Y., assignors to Bendix Aviation Corporation, South Bend, Ind., a corporation of Delaware

Application September 28, 1942, Serial No. 459,988

2 Claims. (Cl. 204—146)

1
This invention relates to salvage systems, and more particularly to the recovery of metal castings in which broken tools have become embedded.

It is fairly common for tools, such as twist drills, taps and reamers, particularly in the smaller sizes, to break during the machining or processing of a metal casting, with the result that the casting must be scrapped if it is impossible to remove the embedded parts by conventional methods or procedures. Quite often, too, during the assembly of a casting having a threaded stud hole, the shank of the stud will break due to defects in the shank or to the application of excessive leverages to the stud head. The conventional procedures for removing broken parts of tools and studs have not been very effective in precision work, and large quantities of castings containing embedded tools must be scrapped completely. As these castings are quite often complex and expensive, the loss through scrapping tends to increase the cost of manufacture and to decrease the production rate of the complete assembly.

It is an object of the present invention to provide a system wherein, by electrochemical processing, parts of embedded metal may be removed from the main body of a casting, a forging or other metal object.

It is another object of the invention to provide an apparatus for removing one metal member from the body of another, which includes means for circulating an electrolyte in the region of the metal to be removed, and making this metal the anode in a circuit which is part of an apparatus for carrying out an electrochemical process.

Other objects of the present invention include the provision of apparatus for continuously circulating a metal solvent through apparatus applied locally for the removal of certain metals from metals of dissimilar basic composition, and also, the use of an electrochemical method for the removal of certain metal members from bodies of dissimilar metallic composition.

Other objects will appear from a study of the following specification when made in conjunction with the attached drawings, throughout which like numerals designate like parts, and wherein the single figure of the drawing is an arrangement, partly schematic and partly in section, of an electrochemical apparatus of the present invention.

Having particular reference to the drawing, 10 is a casting, forging or other body of aluminum or aluminum alloy having a threaded bore 11 in

which is embedded a shank portion 12 of a broken steel stud member. A container 13, which may be a glass funnel, is clamped to a supporting arm 14 carried upon a supporting stand 15, and has a lower throat portion 16 with a smooth open lower edge 17 in contact with the surface of casting 10 surrounding the bore 11.

A tubular rod 18 of brass, having a longitudinal bore 19, projects through the container 13 and has its lower end or tip 20 closely adjacent the open end 17 of throat 16. The upper end of the tube 18 is fixed to an arm member 21 carried by a supporting stand 22. A conduit 23, which may be of rubber or the like, is connected to the top end of tube 18, and extends into the tank or reservoir 24, which contains a liquid 25. A pump 26 is positioned within conduit 23 intermediately of the two ends thereof, and is connected so that it draws liquid from container 13 through bore 19 and into conduit 23, and thus, into reservoir 24. Another conduit 27 is open to tank 24 through port 28, and at its lower end 29, it empties into container 13. A valve 30 is provided in conduit 27 for regulating flow of liquid through conduit 27.

25 The foregoing apparatus is described and claimed in the copending divisional application for U. S. patent Serial No. 516,278, filed December 30, 1943.

30 A source of direct current potential, such as rectifier 31, is provided, and has an anode terminal 32 connected through lead 33 to casting 10 by means of the stud member 34. Rectifier 31 also has a cathode terminal 35, which is connected by means of a clamp 36 and lead 37 to tubular member 18. Rectifier 31 is provided with a power switch 38 and has a current indicator, such as ammeter 39, and a voltage indicator, such as voltmeter 40.

For the removal of steel from aluminum, it has 40 been found that the electrolyte may be ammonium sulfate ($(NH_4)_2SO_4$), and 750 grams per liter of water (H_2O) has been found to be a satisfactory concentration for the electrolyte.

Because of the fact that steel stud shank 12 45 is embedded tightly in bore 11 of aluminum casting 10, shank 12 and casting 10 are in good electrical contact. The system for removing steel stud 12 from aluminum casting 10 is put into operation upon adjustment of the container 50 13 into the position indicated, and the lowering of tube 18 into container 13 to the position shown.

The flow of liquid into container 13 can be 55 adjusted by manipulation of valve 30, and thus, liquid drawn upwardly through bore 19 and into

tank 24 will be replaced in container 13 by sufficient liquid flowing from tank 24 into container 13, so that the process may be carried out continuously.

With the apparatus positioned as shown, current will be conducted through the liquid 25 between stud shank 12, which is an anode, and tube 18, which is a cathode, and by electrochemical action, the stud shank 12 will be gradually dissolved by the ammonium sulfate, which is being constantly renewed by the action of the suction pump 26 in drawing liquid through rod 18 carrying away the removed steel.

The voltage of source 31 should be as high as is practical without introducing arcing and flash-over conditions in the apparatus, but for a given voltage, the amount of current drawn by the circuit will depend principally upon the distance between the anode (12) and the cathode (18). If the anode and cathode are touching, the current drawn as indicated by ammeter 39 will be a maximum, since this is a short circuiting condition. Also, if the anode and cathode are too close, undesired sparking, which will depend upon the value of the voltage chosen for source 31, will occur. Therefore, the optimum distance between anode 12 and the tip 20 of cathode 18, will be that minimum distance which will not cause sparking between the electrodes or short circuiting. Practice will indicate what value of current can be used, and as the optimum value decreases, cathode 18 can be either manually or automatically advanced toward anode 12 to prevent the current as indicated in ammeter 39 from decreasing to too low a value. Just as the steel shank 12 dissolves completely, the current will decrease to zero, indicating complete removal of the steel. The process is completed upon this condition being attained.

The ammonium sulfate does not attack the aluminum casting 10, and at the end of the electrochemical process, all the steel will be dissolved and the threads in bore 11 will be accurate when gauged.

The above explanation sets forth a means whereby steel tools are removed from aluminum castings. The novel process is applicable also to the removal of steel from magnesium bodies and to the removal of steel from brass, bronze, corrosion-resistant steel and other basic metals. An electrolyte for the removal of steel from magnesium may be a solution of hydrofluoric acid in water (H_2O). A 48% solution has been found to operate satisfactorily. In the removal of tool steel from stainless or corrosion-resistant steel, an electrolyte of nitric acid may be used.

It has been stated above that cathode 18 may be automatically advanced toward the stud shank 12 as the shank is dissolved in order to keep the distance between the anode and cathode constant, and thus, obtain the optimum flow of current through the circuit. In practice, this constant distance may be maintained by mounting tubular member 18 so that it may be lowered by pressure imposed, for example, by a weighted member, and by inserting a spacer of an inert material between tip 20 and the top of stud shank 12. This spacer may be a tubular section of glass or conventional plastic material having notches in the bottom part to permit the electrolyte to be freely drawn through bore 19 by pump 26.

Only one embodiment of the invention has been shown and described. The invention, however, is not to be limited to the example contained in the description, but solely by the scope of the appended claims.

What is claimed is:

1. In the salvaging of industrial parts; a method of removing a steel insert from a body of aluminum, which comprises continuously circulating a solution of ammonium sulfate in water in contact with the steel insert, and dissolving the steel insert by anodic treatment in the solution.
2. A method of salvaging an article of manufacture formed of aluminum and having a broken tool part embedded therein formed of steel; comprising the steps of supplying a solution of ammonium sulfate in water in contact with the embedded part; projecting an electrically conducting member into said electrolyte adjacent the embedded part and in spaced relation thereto; providing an external source of electromotive force; electrically connecting said member and part to said external source of electromotive force so as to negatively charge said member and positively charge said part to effect disintegration of said part; circulating the electrolyte in the immediate region of the part so as to disassociate therefrom the disintegrated portions of said part and carry said portions away and free from said article; and adjusting said member in relation to said part so as to maintain a substantially constant distance between said member and part.
